UNITED STATES PATENT OFFICE.

HARRIE A. BALLARD, OF ASHLAND, MASSACHUSETTS, ASSIGNOR, BY MESNE ASSIGNMENTS, TO THE BOYLSTON MANUFACTURING COMPANY, OF BOSTON, MASSACHUSETTS, A CORPORATION OF NEW JERSEY.

MACHINE FOR TACKING SHOES.

No. 844,647.

Specification of Letters Patent.

Patented Feb. 19, 1907.

Application filed April 13, 1903. Serial No. 152,326.

To all whom it may concern:

Be it known that I, HARRIE A. BALLARD, of Ashland, in the county of Middlesex and State of Massachusetts, have invented certain new and useful Improvements in Machines for Tacking Shoes, of which the following is a specification.

This invention has relation to machines for tacking the edge of an upper to the inner sole of a boot or shoe after the inner sole and upper have been placed upon a last, and for the purpose of illustration it is hereinafter described in connection with a tacking-machine of the type described in Letters Patent No. 389,275, granted to E. Woodward, September 11, 1888, although it will be understood that the invention is not limited to the details of that machine. In the machine set forth in that patent there are provisions by which when the shoe is brought into contact with the tacking-applying nozzle mechanism is set in motion whereby a single tack is driven through the edge of the upper and the inner sole, immediately upon which the machine stops automatically. The operator then moves the shoe to a fresh position and effects the driving of another tack. It is necessary for the operator, however, to pull over the edge of the upper by hand in order to stretch the upper properly upon the last and to then tack it prior to its presentation to the tacking mechanism. It has been customary to serrate the lower end of the tacking-nozzle, so as to cause it to assist in some measure in pulling over the edge of the upper; but this pulling-over action has not been satisfactory, as the pincers or the operator's fingers had to be used to draw the upper properly about the last.

This present invention has for its object to provide pincers which are caused to automatically grasp the edge of the upper upon the presentation of the upper thereto, after which the operator may by the manipulation of the shoe cause the pincers to draw the upper taut around the last and practically simultaneously therewith bring the shoe into engagement with the tacking-nozzle, so as to effect the fastening of the upper to the insole. Consequently while the machine is automatic in the sense that the edge of the upper is automatically gripped by the

pincers and the tack is automatically driven into the shoe, yet the operator can draw the leather with the proper tension about the inner sole. This is an important feature of the invention, as leather varies greatly and it is necessary to stretch some grades of leather or even some parts of the upper more than others.

On the accompanying drawings, which illustrate one embodiment of the invention, to which, however, the invention is not limited, Figure 1 represents in side elevation a tacking-machine equipped with the invention, the pincers being separated for the reception of the edge of the upper. Fig. 2 represents a portion of the machine with the pincers grasping the upper. Fig. 3 represents a similar view and shows the upper properly drawn about the last, whereby the driver may force a tack through the upper into the inner sole. Fig. 4 represents a section on the line 4-4 of Fig. 1. Fig. 5 represents a section on the line 5-5 of Fig. 3.

Referring to the drawings, 10 indicates a tack-delivering member or nozzle, and 100 the driver, which is actuated by a horizontal shaft 11, having thereon a path-cam 12 and a loose pulley 13, containing a clutch 14. The movement of the clutch is controlled by a lever 15 and trip mechanism, (shown in dotted lines, Fig. 1,) by which when the nozzle 10 is forced upwardly the shaft 11 is permitted to rotate once, so as to effect the driving of one tack. The mechanism for accomplishing this operation is not fully illustrated, as it forms no part of the present invention, being illustrated in the Letters Patent to Woodward hereinbefore referred to.

The pincer mechanism, which forms the essence of the invention and which is used in connection with the tacking mechanism, will now be described.

Referring to Fig. 1, it will be seen that journaled on a stud 17, projecting from the head of the machine, there is a lever 18, whose rear end 19 is forced upwardly by a spring 20. The other end of the lever is bent upwardly in front of the tack-driver end and is apertured, as at 21, to receive the nozzle of the tacking mechanism. This lever forms one jaw of the pincer, being provided with a wiping-surface *a* and with a serrated portion *b* for coaction

with the relatively movable pincer member. The last-mentioned member is indicated at 22, and it is pivoted to a stud 23 on the upwardly-extending portion 24 of the lever 18. 5 A strong leaf-spring 25 is interposed between the two members 22 and 24 for the purpose of throwing the upper end of the member outwardly, and thereby causing its lower end to move toward the serrated portion *b* of the 10 other member. The said member 22 is provided with a serrated end *b'*, complementary to that at *b*. From this description it will be seen that the edge *c* of the upper of a shoe (indicated at A) may be inserted between the 15 two pincer members, after which the members may be caused to clamp it between them, as shown in Fig. 2.

It will be observed that the member 22 is provided with guides 26 27 for the reception 20 of what may be termed a "feeler" 28. The lower end of this feeler projects downwardly below the end of the pincer member 22, so that it may be engaged by a shoe. A spring 29 bears against a flange on the feeler and 25 holds it yieldingly in the position shown in Fig. 1. The upper end of the feeler is provided with a pin or trip member 30, which is jointed thereto and which when the feeler is depressed is drawn into the guide 27, so as to 30 hold it in alignment with the body of the feeler.

31 indicates a hooked latch, which lies in a slot in the top of the member 22 and the hook of which is adapted to hold said pincer member in its open position with the jointed member 30 beyond its inclined end, as shown. 35 This hooked latch 31 is bent around the driver-bar 100 and is connected to an arm 33 on an upright shaft 34, journaled in a bearing 35, formed on the head of the machine. To the upper end of the rock-shaft 34 and in vertical alignment with the arm 33 is connected another arm 36, held against the rear face of the cam 12 by a spring 37. (See Fig. 4.) The rear face of the cam 12 is formed 40 with a rise or projection *d* for rocking the arm 36, and thereby rocking the shaft 34 to move the hooked latch 31, as will be subsequently explained.

50 In practice the operator presents a shoe to the machine substantially as shown in Fig. 1. The sole of the shoe is held below the feeler 28, and the edge *c* of the upper is inserted between the serrated jaws of the pincer members. The upward movement of the shoe in the insertion of the upper forces upward the feeler 28, so as to cause the member 30 to lift the latch 31 and release the upper end of the pincer member 22. The spring 25 there 55 upon immediately throws the member 23 over, so as to close the pincers upon the upper, as shown in Fig. 2. The operator is then able to draw the upper around the last and lay it upon the inner sole by means of the 60 flat wiper-face *a* on the lever 18. As this is

being accomplished the operator is moving the shoe upward, the lever 18 yielding to permit this until the folded-over portion of the upper comes in contact with the lower end of the nozzle 18, after which the continued movement of the shoe lifts the nozzle and sets in motion the tacking mechanism. After one tack is driven the machine stops. During the rotation of the shaft 11, which 70 effects the driving of the single tack, the arm 36 rides off from the bunch or projection *d* on the cam 12, and the latch 31 moves forward, so that its hook takes over the upper end of the pincer member 22, as shown in Fig. 3, and as the shaft completes its revolution the projection or rise *d* forces back the arm 36, so as to rock the shaft 34 and draw the hooked latch 31 to the right in Fig. 1, so as to open the pincer member 22 and hold it in open position, and as the shoe is moved 80 downward by the operator the feeler 28 is permitted to move down, so that its member 30 is carried into position under the latch, as shown in Fig. 1.

For the purpose of feeding tacks singly to 90 the tack-driving mechanism mechanism is provided consisting of an upright rock-shaft 40, carrying an arm 41 with a roll 42 entering a cam-groove in a cam 43 on a shaft 11. To the lower end of said shaft is secured an 95 inwardly-projecting arm 44. To this arm is connected a slide 45, having a downwardly-projecting pin 46, entering a cam-slot 47 in a plate 48, suitably supported by a bracket. The end of the slide carries a finger 49, which 100 is adapted to enter into the delivery-chute 50 and separate the foremost tack from the others and place it in the position to be engaged by the end of the driver. The groove 47 is so formed that as the slide 45 moves 105 rearward the finger 49 is moved outward from the tack-chute and rearward into position, so that when it is again moved forward it engages the first tack in the row and forces it into the aperture in the nozzle. 110

From this description it is apparent that the operator may manipulate the upper as much as he desires by the aid of the pincer before he sets the machine in motion to feed a tack to the driver and effect the driving of the tack. Consequently he is able to last the shoe properly during the tacking operation. 115

It will be understood that the shoe is mounted upon a jack, by which the operator may with his foot move the shoe vertically and also in a horizontal direction relatively to the pincers. As this mechanism, however, is well known, it is not illustrated.

Having thus explained the nature of the invention and described a way of constructing and using the same, although without attempting to set forth all of the forms in which it may be made or all of the modes of its use, I declare that what I claim is— 125

1. In a tacking-machine, tack-driving 130

mechanism, including a reciprocatory driver, and pincers pointing downwardly for grasping the upper by the edge, and movable manually toward and from the tack-driving mechanism, in lines longitudinal of the reciprocation of the said driver.

2. In a tacking-machine, tack-driving mechanism including a reciprocatory driver, pincers pivoted together between the path of said driver and the operator for grasping the edge of the upper, and means for pivotally supporting said pincers whereby they are movable manually toward and from the tack-driving mechanism.

15 3. In a machine for driving tacks, automatic tack-driving mechanism comprising a movable delivery-nozzle, and means rendered active by the movement of said nozzle for causing the actuation of the tack-driving mechanism, and pincer mechanism having an open space occupied by the said nozzle and movable by the engagement of a shoe therewith to expose the nozzle for the engagement of said nozzle by the said shoe.

25 4. In a machine for driving tacks, automatic tack-driving mechanism comprising a movable delivery-nozzle, and means rendered active by the movement of said nozzle for causing the actuation of the tack-driving mechanism, and pincer mechanism pivoted to the machine and having an open space occupied by the said nozzle, and carrying a movable pivot by which the pincer-jaws are connected, said pincers being bodily movable by engagement of a shoe therewith to expose the nozzle for the engagement of the said nozzle by the said shoe.

35 5. In a tacking-machine, tacking mechanism, bodily-movable upper-gripping mechanism for engaging the upper of the shoe, and adapted to draw the upper over the shoe by manual movement of the shoe preliminary to the action of the tacking mechanism, and means for pivotally connecting the gripping mechanism to the machine to move toward and from the end of the tacking mechanism, substantially as and for the purpose set forth.

45 6. In a tacking-machine, tacking mechanism, and a normally open pincer having means whereby the pincer automatically grips the upper upon bodily movement of a part of said means caused by contact of a shoe therewith in advance of the operation of the machine.

55 7. In a tacking-machine, tacking mechanism, a bodily-movable automatic pincer for automatically gripping the upper upon the presentation of a shoe thereto, and whereby manipulation of the shoe relatively thereto effects a stretching of the upper about the last, means adapted to be moved by a shoe to render the tacking mechanism active, movable means for supporting said pincer and for normally protecting said last-men-

tioned means from external interference, but adapted to be moved by a shoe to expose said protected means for the purpose set forth.

8. In a tacking-machine, tacking mechanism including driving mechanism, and a movable nozzle automatically controlling the driving mechanism, in combination with a pincer, means for supporting said pincer whereby it is adapted to move in lines longitudinal of the movement of the said nozzle to permit the engagement of a shoe with said nozzle, and means for automatically closing the pincer on the edge of the upper preliminary to the actuation of the nozzle by the shoe.

15 9. In a machine for inserting fasteners, the combination with an initially open pincer, of a spring for closing said pincer upon the work, and means adapted to be actuated by the shoe to permit the spring to close the pincer for the purpose of gripping the upper.

20 10. In a tacking-machine, tacking mechanism including driving mechanism, and a movable nozzle automatically controlling the driving mechanism, in combination with a bodily-movable pincer having an open space occupied by said nozzle and normally obstructing the contact of a shoe with the nozzle but movable to permit said contact, said pincer having jaws for grasping the edge of the upper.

25 11. In a tacking-machine, tacking mechanism including driving mechanism, and a movable nozzle automatically controlling the driving mechanism, in combination with a pincer having an open space occupied by said nozzle and normally obstructing the contact of a shoe with the nozzle but movable to permit said contact, said pincer having jaws and means whereby said jaws are permitted by a pressure of the shoe to close upon said upper.

35 12. In a machine for driving fasteners, a pincer formed with coacting jaws and with a wiping portion, and means controlled by the shoe on presentation to the pincers for causing said jaws to close on the work.

45 13. In a machine for driving fasteners, a pincer formed with coacting jaws, a spring for closing said jaws, means for holding the jaws open, and a feeler adapted to be engaged by the shoe in the insertion of the upper between the jaws for tripping said holding means.

55 14. In a tacking-machine, driving mechanism including a nozzle, a pincer movable in lines longitudinal of the nozzle, means for holding the pincer-jaws open, and a device operable by the movement of the shoe toward the nozzle for tripping said means.

60 15. In a machine for driving fasteners, a pincer formed with coacting jaws, a member for holding said jaws open, a device for tripping said holding member and thereby per-

mitting said jaws to close upon the work, and means for automatically moving said member to reopen and hold said jaws.

16. In a machine for driving fasteners, a pincer formed with coacting jaws, a spring for closing said jaws, a member for holding the jaws open, a feeler for tripping said member, and means for automatically causing said member to open said jaws.

17. In a tacking-machine, driving mechanism including a nozzle, a pincer movable in lines longitudinal of the nozzle, a member for holding the pincer-jaws open, a device operable by the movement of the shoe toward the nozzle for tripping said member, and means for automatically causing said jaws to be opened by said member.

18. A tacking-machine comprising a power-shaft, a pincer having movable jaws, a latch for holding said jaws open, means operated by the contact of the shoe for tripping said latch, and means actuated by said shaft for reengaging said jaws by said latch.

19. In a shoe-tacking machine, tack-driving mechanism, a pincer, a movable shoe-

engaging member, and automatic means adapted to be engaged by said member and to be rendered active when moved thereby for causing the pincer to grip the upper independently of said driving mechanism.

20. In a tacking-machine, the combination with automatic tack-driving mechanism and a movable delivery-nozzle controlling the operation thereof, of a pincer having an open space occupied by said nozzle and having jaws for grasping the edge of the upper farthest from the operator so that when the shoe is manually forced away from the operator the upper is drawn over the edge of the last, and the drawn-over portion presented to the delivery-nozzle, and means for movably connecting said pincer so that the jaws thereof move in the direction of movement of said nozzle.

In testimony whereof I have affixed my signature in presence of two witnesses.

HARRIE A. BALLARD.
